UNITED STATES PATENT OFFICE.

HERMAN IHLENBURG, OF PHILADELPHIA, PENNSYLVANIA, ASSIGNOR TO
DAVID WOLFE BRUCE, OF NEW YORK, N. Y.

DESIGN FOR TYPE.

SPECIFICATION forming part of Design No. 15,038, dated June 3, 1884.

Application filed April 10, 1884. Term of patent 14 years.

To all whom it may concern:

Be it known that I, HERMAN IHLENBURG, (assignor to DAVID WOLFE BRUCE,) of the city and county of Philadelphia, Pennsylvania, have invented and produced a new and original design for a font of printing-type, of which the following is a specification.

The nature of my design is clearly shown in the accompanying typographic impression; and it consists of an ornamented letter having the heavy triangular termination at the base, as shown in the A, B, D, E, F, H, I, K, L, M, N, P, T, V, W, and X, which triangular termination is also found at the top of the B, 15 D, E, F, H, I, J, K, L, M, N, P, U, V, W, X, and Y. In the A, H, M, and W the central lines of the letter are lighter than the up and down portions, and looped, as shown. The curved line with dot-termination is found upon 20 the upper left hand of the A and Z, and upon the upper right hand of the F, L, N, and P, in the lower right-hand termination of the C and Z, in the cross-line of the E K, in both the upper terminations of the T, and in the lower

left-hand termination of Y and the termination of the symbol &. In the letter R the heavy triangular terminations are found at the top and bottom of the up-and-down portion, and in the lower right-hand termination. The upper right-hand portion is spurred, as 30 shown, and the central portion of the letter is looped, as shown. Several of the letters, notably the B, D, G, O, Q, and U, are either spurred or ornamented by the heavy dot, as shown, and the inclined line with dot termination following the curved ends of the same crosses the S, as shown.

The character of the design is preserved in the punctuation-marks, the numerals, and in the dollar and pound marks.

Having now described my invention, I claim as new—

The design for a font of printing-type, substantially as shown and described.

HERMAN IHLENBURG.

In presence of—

SAML. M. BROWN,
CHARLES BROWN.
